Attorney

UNITED STATES PATENT OFFICE.

FRED W. JONES, OF SWANWICK, ILLINOIS.

WRENCH.

1,335,688.

Specification of Letters Patent. Patented Mar. 30, 1920.

Application filed August 14, 1919. Serial No. 317,519.

To all whom it may concern:

Be it known that I, FRED W. JONES, a citizen of the United States, residing at Swanwick, in the county of Perry and State of Illinois, have invented certain new and useful Improvements in Wrenches; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in wrenches, especially designed for pulling bolts either with or without heads.

The invention comprises a simple and efficient device of this nature having various details of construction, combination and arrangement of parts, which will be herein-after fully described, shown in the accompanying drawings and then specifically defined in the appended claim.

My invention is illustrated in the accompanying drawings which, with the letters of reference marked thereon, form a part of this application, and in which:

Figure 1 is a side elevation of my wrench.

Fig. 2 is a similar view taken from the opposite side.

Fig. 3 is a detail perspective of the insertible movable jaw, and Fig. 4 is a sectional view on line 4-4 Fig. 3.

Reference now being had to the details of the drawings by letter:

A designates a fixed jaw having a handle B integral therewith. One face of the jaw

is recessed as at C and has a shoulder D 40 about a portion thereof, and is apertured at F for the reception of a pivotal bolt H, having a nut H' thereon. A plate I, preferably of the shape shown in Fig. 1, is pivotally mounted upon said bolt and has 45 a dove-tailed recess L upon its inner face adapted to receive a shank portion K of an adjustable jaw N, which latter has an L-shaped portion with serrations O upon one edge thereof, adapted to coöperate with the 50 serrations A' upon the fixed jaw to grip and hold a bolt or other object to be pulled.

Said jaw N is held in different positions within the dove-tailed recess by means of a screw R mounted in an aperture in the 55 plate I.

By the provision of a wrench embodying the features of my invention, it will be noted that means is provided whereby the device may be adjusted to grip bolts of different diameters by simply adjusting the sliding jaw in different positions relative to the fixed jaw, and by swinging the fixed jaw back and forth the bolt may be gripped and pulled.

What I claim to be new is:

A wrench comprising a fixed jaw with an integral handle, the face of the jaw being recessed, a plate pivotally mounted in said recess and having a dove-tailed recess upon 70 its inner face, a sliding jaw having a shank portion with dove-tailed connection with the plate, and a screw for holding the sliding jaw in an adjusted position.

In testimony whereof I hereunto affix my 75 signature.

FRED W. JONES.
